UNITED STATES PATENT OFFICE.

PAUL H. SCHENDLER, OF ERIE, PENNSYLVANIA.

FEED MECHANISM FOR CLOTHES-WRINGERS.

1,355,006.

Specification of Letters Patent.

Patented Oct. 5, 1920.

Application filed December 3, 1919. Serial No. 342,119.

To all whom it may concern:

Be it known that I, PAUL H. SCHENDLER, a citizen of the United States, residing at Erie, in the county of Erie and State of Pennsylvania, have invented certain new and useful Improvements in Feed Mechanism for Clothes-Wringer; and I do hereby declare the following to be a full, clear, and exact description of the invention, such as will enable others skilled in the art to which it appertains to make and use the same, reference being had to the accompanying drawings, and to the letters of reference marked thereon, forming part of this specification.

15 This invention relates to clothes wringers, and the object thereof is to provide mechanism adapted to feed the cloth to the rollers of a clothes wringer so that it will not be necessary to use the fingers for that purpose, thus eliminating the danger of the fingers of the operator being caught and drawn between the rollers.

20 That this danger is real will be understood by those who use clothes wringers which are operated by mechanical power.

25 Another object of my invention is to so construct such a feeding mechanism that it can easily be changed from one side of the wringer to the opposite side, which is highly desirable with power driven wringers, as it is frequently necessary to reverse the direction of rotation of the rollers, and feed from the opposite side.

30 In my former Patent No. 1,230,928 dated June 19, 1917, I show and describe mechanism for feeding a clothes wringer, but there are certain difficulties incident to the construction therein shown and described, which I have overcome in the present invention.

35 In carrying out my present invention I suspend on the side of the wringer frame a stationary plate upon which is placed a sliding plate which is adapted to slide toward the meeting point of the two rollers and to recede backward therefrom; and mounted under the stationary plate are rollers which contact against the lower of the two wringer rollers so that as the wringer rollers revolve, 40 the rollers contacting with the wringer rollers will revolve in unison therewith; and I connect the sliding plate with said contacting rollers by means of pitmans so that the sliding plate is caused to slide toward and 45 from the wringer rollers.

These and other features of my present invention are hereinafter described and pointed out and are illustrated in the accompanying drawings in which:

Figure 1, is a side elevation of a clothes wringer having my improved feeding mechanism in place thereon.

Fig. 2, is a transverse section thereof on the line 1—1 in Fig. 1.

In these drawings A A indicate the end posts of a clothes wringer of ordinary construction, and B B indicate the rollers of the wringer. C is a stationary plate which has ears C' C', which are provided with key-hole openings c which are adapted to hook over screws or studs D secured in the end posts A A so that the plate C can be readily put in place on the wringer or removed therefrom.

Projecting downwardly from the plate C are ears E E in which is journaled a rod E' on the ends of which are secured rollers E² E² which rest against the lower wringer roller B and support the plate C. Upon the plate C is a slidable feed plate F which is provided with ears F' F' which project downwardly through transverse slots c' in the stationary plate C and serve to guide the plate F. The ears F' F' on the feed-plate F and the rollers E² E² are connected by means of pitmans G so that as the rollers E² are caused to rotate by reason of this contact with the lower wringer roller B the feed plate F is caused to reciprocate toward and from the wringer rollers, and as the plate F moves forward toward the rollers it will tuck the edge of a garment between the wringer rollers, thereby eliminating the necessity of using the fingers for that purpose.

95 To further guard against accident I have provided a guard roller H which is pivoted in ears H' on the ends of the stationary plate C, said roller H being so positioned that it is directly in the path of the operator's hand, if moved toward the wringer rollers; and the roller H also acts to hold the garments off of the feeding plate F and renders their passage thereover easy. J indicates an off-bearing board, which, like the feeding device heretofore described, can be shifted to either side of the wringer. It is interchangeable with the said feeding device. To insure the traction of the rollers E², on the lower wringer roller B I provide springs K which 105

tend to pull the plate C downward so that the rollers E² are thereby pressed against the lower wringer roller.

From the foregoing description, and the illustration of the drawings, it will be evident that my improved feeding device is adapted to be secured upon a clothes wringer by simply affixing two screws D in the proper position on the end posts thereof.

- 10 Having thus fully shown and described the construction and operation of my invention so as to enable others to utilize the same what I claim as new and desire to secure by Letters-Patent is:—
- 15 1. In a device of the class described, a stationary plate, means to removably secure the same on a clothes wringer frame adjacent to the intake side of the wringer rollers, a slideable feed-plate upon said stationary plate, and traction mechanism operated by one of the wringer rollers to cause said feed-plate to reciprocate toward and from said wringer rollers.
- 20

2. In a device of the class described, a stationary plate, means to removably secure 25 the same on a wringer frame, a slideable feed-plate upon said stationary plate, rollers mounted under said stationary plate and contacting with the lower roller of the wringer and pitmans actuated thereby to 30 operate said feeding-plate, substantially as set forth.

3. In a device of the class described, a bracket plate, a slideable plate on said bracket plate, a shaft under said bracket plate, 35 wheels on said shaft, pitmans pivoted eccentrically to said wheels, and to said feeding plate, substantially as set forth.

4. In a device of the class described, a bracket plate, a slideable feed plate on said 40 bracket plate, means to actuate said slideable plate, and a guard roller above said slideable plate, substantially as set forth.

In testimony whereof I affix my signature.

PAUL H. SCHENDLER.
